H. R. HUGHES,
ROTARY DISK DRILL,
APPLICATION FILED DEC. 29, 1916.

1,227,911.

Patented May 29, 1917.

Howard R. Hughes, Inventor

By his Attorney

Gen. M. [Signature]

UNITED STATES PATENT OFFICE.

HOWARD R. HUGHES, OF HOUSTON, TEXAS, ASSIGNOR TO HUGHES TOOL COMPANY, OF
HOUSTON, TEXAS, A CORPORATION OF TEXAS.

ROTARY DISK DRILL.

1,227,911.

Specification of Letters Patent. Patented May 29, 1917.

Application filed December 29, 1916. Serial No. 139,620.

To all whom it may concern:

Be it known that I, HOWARD R. HUGHES, a citizen of the United States, residing at Houston, in the county of Harris, State of Texas, have invented new and useful Improvements in Rotary Disk Drills, of which the following is a specification.

This invention relates to rotary boring drills of a type known commercially as "disk drills," which are equipped with one or more substantially disk-shaped cutters rotably mounted and arranged in a substantially upright position in the head of the drill, the drill in my present invention being similar to that type of drill disclosed in my Patent No. 1204157, on which device it is an improvement.

The object of my present invention is to provide a practicable disk drill that is efficient and strong, and so arranged as to be inexpensive of manufacture and easily kept in serviceable condition.

Another object is to mount the cutters on the lower portion of the drill head in such manner that the upper portions of these cutters are housed by an overhanging portion of the drill head to thus more fully protect them when the drill is in operation, and to further tend to lessen packing of cuttings or disintegrated material from the bottom of the hole being drilled around the cutters in such manner as to prevent ready rotation of the cutters upon their bearings.

Still another object of my present invention is to so arrange the water courses through the drill head that the lower ends thereof open in the recesses in the drill head housing the cutters, the outlets of these water courses being located inside of the cutters to thus bring the full force of the water issuing therefrom to bear upon the upper portion of the cutters. This arrangement of water courses tends to wash the cutters clear of disintegrated material and further to prevent the influx of such disintegrated material to the space or clearance between the upper portions of the cutters and the adjacent walls of the drill head.

Other objects and desirable features of my invention will be hereinafter pointed out and will appear in the description thereof.

In the drawings illustrating my invention and in which like characters of reference designate like parts:

Figure 1 is a side elevation of the bit forming the subject of my invention, parts

thereof being shown in section and other parts removed to better illustrate the invention.

Fig. 2 is a side elevation of the drill disclosed in Fig. 1, taken at right angles to Fig. 1.

Fig. 3 is an end view of the device, with the cutters removed.

Referring to the drawings which illustrate the preferred form of my invention, "A" designates the head of the drill, which is provided at its upper end with an externally threaded portion 1 adapted to receive a collar, not shown, which collar is in turn adapted to receive the end of a hollow drill stem, also not shown. The lower end of the head A is cut away on each side, as clearly shown at 2, a spindle 3 being rigidly connected to this cutaway portion of the drill head. Mounted upon the spindles 3 are substantially disk-shaped cutters B, which cutters are arranged in a substantially upright position on the head A. As shown, each cutter is provided with a beveled edge that has cutting teeth 4 thereon, extending transversely across the same, and in addition is provided on its inner side with a tapered portion having teeth 5, as most clearly shown in Fig. 1. The precise method of mounting these cutters upon the spindles forms no part of this invention, but any of the methods shown in my various patents, such as my patent above referred to, may be used. Further, the precise form of the disk cutters is not important in so far as regards my present invention, for any of the usual form of such cutters may be used without departing from the spirit of my invention.

At the upper end of each cutaway portion, the drill head is recessed to form a pocket-like recess 6. The walls of this pocket-like recess are so shaped as to conform to the shape of the disk cutters used. The upper wall of this recess extends radially a sufficient distance to overhang the cutters, and this wall is further shaped to conform to the circumference of the disks being extended longitudinally of the drill head a sufficient distance to shroud or overhang a substantial portion of the disks. In other words, the walls of these pocket-like recesses are shaped to conform to the shape of the cutting disks, and the recesses are of such depth radially and longitudinally that the walls thereof completely house or shroud a substantial portion of the disks. As used in

the claims appended to this specification, the statement, that the walls of the recesses in which the cutting disks work are shaped to conform to the shape of the cutters, has reference to the immediately foregoing description. The entire convex side of the recess is shaped to conform to the entire concave side of the disk, as is clearly shown in Fig. 1. As best shown in Fig. 2, the upper walls of the recesses are so arranged with relation to the periphery of the disk cutters that the clearance or space between such walls and the periphery of the cutters increases progressively in the direction of rotation of the cutters. It is evident, therefore, that packing of cuttings or disintegrated material around the disk cutters in the housing recesses will be eliminated, for any material sufficiently small to pass the point Y will be readily accommodated by all other portions of the clearance space, inasmuch as movement through this space because of rotation of the cutters will bring such material progressively into the increasing clearance space. It is evident, therefore, that clogging is eliminated and sticking or binding of the rollers prevented.

Arranged longitudinally through the head is a plurality of water passages 7, the upper ends of which are located in the reduced extension 1. The lower ends of these water passages open into the pocket-like recesses 6 and are so located in these recesses that jets of water issuing therefrom strike against the inner faces of the cutting disks, as clearly shown in Fig. 1, these passages being so arranged that jets of water issuing therefrom strike the cutters at an angle, the line of movement of such jets of water being contrary to the direction of rotation of the cutters. This arrangement further tends to prevent the influx of disintegrated material into the pocket-like recesses, for the jets of water issuing from these passages enter the pocket-like recesses at points therein adjacent to that portion of the clearance space between the walls of the recesses and the peripheries of the cutters through which disintegrated material enters into such pocket-like recesses. And the currents of water being directed against the peripheries of the disks and flowing contrary to the direction of rotation would tend to prevent the entrance of material carried by the disks into the clearance space.

In assembling this device, the disk cutters are moved radially into the pocket-like recesses and on to the spindles 3, after which retaining devices are applied to the ends of the spindles.

Upon the upper end of the drill head and as a still further reduced extension upon the reduced extension 1 is located a threaded sleeve 8 adapted to receive a lubricant 65 retainer, not shown.

From the above description, it is evident that the drill forming the subject matter of this invention is very rugged of construction, is composed of few parts, and is so constructed that the cutting disks are housed or shrouded so as to furnish ample protection therefor, and to further protect those cutting disks from the packing or clogging of material therearound, which would tend to prevent rotation thereof when the drill is in operation, and thus cause the cutting disks to drag, which would result in the rapid wearing out of these disks.

Having thus described my invention, what I claim and wish to secure by Letters Patent is:

1. A drill comprising a head, recesses in opposite sides of one end of the head, disk-shaped cutters mounted in the recesses, the inner walls of the recesses shaped to conform to the shape of the cutters, the upper walls of the recesses extending radially entirely over the upper part of the cutters, and water courses opening into the recesses adjacent the cutters.

2. A drill comprising a head, recesses in opposite sides of one end of the head, spindles upon the head, and projecting into the recesses, disk-shaped cutters mounted on the spindles, the upper walls of the recesses extending radially to overhang the cutters, said walls being shaped on the inner side to conform to the peripheries of the cutters and so extended as to house a substantial portion of the cutters.

3. A drill comprising a head, recesses in opposite sides of one end of the head, disk-shaped cutters mounted in the recesses, the inner walls of the recesses conforming to the shape of the cutters and the upper walls extending radially and longitudinally to cover a substantial part of the cutters, and water passages opening into the recesses inside the cutters.

4. A drill comprising a head the lower end of which is cut away on both sides, pockets in the head adjoining the cutaway portions, disk shaped cutters mounted on the cutaway portions of the head, the upper parts of these cutters extending into the pockets, the upper walls of the pockets extending radially and longitudinally of the drill head to entirely house a substantial portion of the upper part of the cutters, and water passages opening into the pockets inside the cutters.

5. A drill comprising a head the lower end of which is cut away on both sides, that part of the head at the upper end of the cutaway portion being recessed on both sides, disk-shaped cutters partly housed in the recesses, the upper walls of the recesses entirely overhanging the cutters and covering a substantial portion of the upper part of the periphery thereof, water courses open-

ing into the recesses through the upper walls thereof adjacent one side and inside the cutters, such courses being so arranged that jets of water issuing therefrom strike the peripheries of the cutters at an angle, the flow of said jets of water being contrary to the direction of rotation of the cutters.

6. A drill comprising a head the lower end of which is cut away on opposite sides, recesses in the head at the upper end of the 10 cutaway portions, disk-shaped cutters mounted on the cutaway portions, the upper parts of the cutters extending into the recesses, the inner walls of the recesses being shaped to conform to the shape of the cutters, the upper wall of each recess being extended radially to overhang the cutters, the depth of the recesses being such that substantial portions of the cutters are 15 housed therein, water courses opening into the recesses and so arranged that jets of water issuing therefrom will strike against the inner faces of the cutters adjacent to side walls of the recesses, the current of said 20 jets being in a direction contrary to the rotation of the cutters.

7. A drill comprising a head, the lower end of which is cut away on both sides, that part of the head at the upper end of the 25 cut-away portion being recessed on both sides, disk-shaped cutters partly housed in the recesses, the upper walls of the recesses entirely overhanging the cutters and covering a substantial part of the upper portion 30 of the periphery thereof, these walls being so arranged that the space between each wall and the periphery of the corre-

sponding cutter increases progressively in the direction of rotation of the cutter, water courses in the head opening into the recesses and so arranged that jets of water therefrom issue into the small end of the space between the walls of the recesses and the peripheries of the cutters, the flow of such jets of water being at an angle to the 40 longitudinal axis of the drill head and against the direction of rotation of the cutters.

8. A drill comprising a head, the lower end of which is cut away on both sides, that 45 part of the head at the upper end of the cut-away portion being recessed on both sides, disk shaped cutters partly housed in the recesses, the upper walls of the recesses entirely overhanging the cutters and covering a substantial part of the upper portion 50 of the periphery thereof, the said upper walls being so arranged that the clearance between these walls and the peripheries of the cutters is greater at one side of the recesses than at the other, this clearance increasing progressively in the direction of rotation of the cutters, water courses in the head opening into the recesses adjacent the 55 side of least clearance, and so arranged that jets of water issuing therefrom impinge upon the periphery of the cutters at an angle, the flow of such water being contrary to the direction of rotation of the cutters.

In testimony whereof, I hereunto affix my 60 signature this the 26th day of December, 1916.

HOWARD R. HUGHES.
